UNITED STATES PATENT OFFICE.

HERMAN OSSWALD, OF RICHMOND HILL, NEW YORK, ASSIGNOR TO THE V. & O. PRESS COMPANY, A CORPORATION OF NEW YORK.

SAFETY-GUARD FOR PRESSES.

1,392,699.

Specification of Letters Patent.

Patented Oct. 4, 1921.

Application filed April 15, 1918. Serial No. 228,565.

To all whom it may concern:

Be it known that I, HERMAN OSSWALD, a citizen of the United States, residing at Richmond Hill, in the county of Queens, State of New York, have invented certain new and useful Improvements in Safety-Guards for Presses; and I do hereby declare the following to be a full, clear, and exact description of the invention, such as 10 will enable others skilled in the art to which it appertains to make and use the same.

This invention relates to safety devices for presses and is directed particularly to the provision of an improved form of guard 15 to be applied to punch presses and like machines to protect the operator against injury.

The invention is of special utility in punch presses of the type wherein a treadle 20 is depressed to actuate a clutch whereby the operating shaft of the machine is connected to the power wheel to cause it to make one revolution and then come to rest if the treadle be released at once or to continue in 25 operation so long as the treadle is held depressed. One feature of the invention involves the provision of means for guarding against the possibility of injury to the operator in case the treadle is depressed to operate 30 the clutch and immediately released. In many forms of press guards as heretofore constructed, provision has been made for lowering a guard over the lower die as the pedal of the machine is depressed, but in 35 these machines the release of the pedal immediately after it is depressed to operate the clutch results in the return of the pedal by its retracting spring and elevation of the guard. Such a construction admits of the 40 possibility of injury to the operator as a result of reaching in under the guard after the latter has been raised with the raising of the pedal and before the operating shaft has rotated sufficient to carry the upper die 45 downward into engagement with the lower die. One of the objects of the present invention is to improve upon the construction of press guards of this type as heretofore constructed by insuring that when the guard 50 is lowered as an incident to depression of the pedal, it will remain in its lowered position, preventing the operator from inserting his hand under the upper die, until the operating shaft has rotated far enough to 55 completely eliminate the possibility that the

operator may get his hand between the dies while the upper one is moving downward.

The invention also involves the provision of an improved form of press guard which is simple in construction, which may be manufactured and installed at low cost, which is reliable in operation, and which is adapted for ready adjustment in accordance with changes of the position of the rocking frame of the press upon the pedestal.

The features of the invention will be better understood by reference to the following description taken in connection with the accompanying drawings, in which Figure 1 is an elevation of a punch press provided 70 with my improved protective device; Fig. 2 is a front view of the press; Fig. 3 is a horizontal section on line 3—3 of Fig. 1; Fig. 4 is a sectional detail view on line 4—4 of Fig. 1; Fig. 5 is a perspective view of the 75 controlling member; Fig. 6 is a perspective view of the clutch dog; Fig. 7 is a vertical sectional detail view through the clutch dog; Figs. 8 and 9 are sectional detail views corresponding to Fig. 7 and illustrating different 80 positions of the parts; and Fig. 10 is a view of a portion of the operating shaft showing the controlling member in section.

Referring to these drawings, 11 indicates the pedestal of the press and 12 the upper 85 frame which is pivotally mounted upon pedestal 11 to permit it to be arranged in the vertical position shown in Fig. 1 or turned to any desired position of inclination with respect to the vertical. For this 90 purpose the rocking frame 12 is pivotally mounted upon the pedestal 11 to turn about the axis 13; also, a rod 14 on the rocking frame passes through arc-shaped slots 15 on the pedestal and adjusting devices 16 are 95 provided whereby the rocking frame may be turned about the axis 13. The construction of the press as a whole in these and other respects may be and preferably is that illustrated and described in Patent No. 100 769,955, granted to me September 13, 1904.

The operating shaft 17 is mounted in bearings on the rocking frame which overhang the bolster 18 upon which the die 18' is mounted, the construction being such that 105 the slide 10 may be extended up in rear of the operating shaft 17 to provide an elongated bearing surface in the guideway provided for the slide in the frame 12. On the shaft 17 is an eccentric 47 for reciprocating 110

the slide and the upper die in the usual manner. The power wheel 19 is mounted loosely upon one end of the operating shaft 17. In the face of one of the hubs of the power wheel are recesses 20. Adjacent to this hub of the wheel 19 the power shaft 17 is provided with an enlargement 21 and in this enlargement is a guideway extending parallel to the axis of the shaft for the reception of a dog 22. The dog is shown in perspective in Fig. 6. Within it is a recess for a spring 23, one end of which engages the bottom of the recess and the other end of which engages a stud or projection 24 on the enlargement 21 so that the spring exerts a pressure on the dog continuously tending to move it to project its end into one of the notches or recesses in the hub of the power wheel 19.

In the enlargement 21 of the operating shaft is a circumferential groove and the dog 22 is provided with a recess which alines with this groove when the dog is in its retracted position. The groove in the enlargement 21 and the recess in the dog 22 are adapted for coaction with a controlling member 25, shown in perspective in Fig. 5. This controlling member is mounted for movement in the direction of its length in a guideway formed on a plate 26 which is secured to one of the side frames of the press. Suitable provision is preferably made for permitting the mounting of the plate 26 upon the frame of the press in any position within a prescribed angular range about the axis of the operating shaft 17. The controlling member 25 has a stem 27 secured to it and passing through an opening in a guide formed on the plate 26. A spring 28 is coiled upon the stem 27 and is under compression between the controlling member 25 and the guide for the stem. The spring therefore tends constantly to press the controlling member 25 forward into the groove in the hub 21. The end of the stem 27 is pivotally connected to a lever 29 which is pivotally mounted upon the plate 26.

The controlling member is operated to withdraw it from the groove in the hub by means of a pedal 30 pivoted upon the pedestal of the machine and held yieldingly in a raised position by a coiled spring 31. A rod 32 is pivotally connected at its lower end to the pedal 30 and at its upper end to the supporting frame of the press guard. Referring to Fig. 3, it will be seen that a rock shaft 33 extends between the side frames of the press and is adapted to rock in bearings formed therein. On one end of the shaft 33 is a crank 34 to which the upper end of rod 32 is secured by a screw 35 which permits of securing rod 32 to crank 34 at any position along the length of the rod required by the angular position of the 65 rock frame 12 on the pedestal 11. On

the rock shaft 33 is secured a support 36 carrying the press guard 37 which may be of any desired construction. In the present instance it is shown as a rectangular frame of a size adapted to inclose the die 70 19 when the guard is depressed, and this frame may have a wire lattice or any similar form of protective device mounted thereon. A second rod 38 is secured to the crank 34 by a screw 39 similar to the screw 35, 75 and extends upwardly therefrom to the pivoted lever 29 to which it is pivotally connected.

Referring more particularly to Figs. 5 to 10 inclusive, it will be noted that one wall 80 40 of the recess in the dog 22 is curved or inclined and that the forward end of the controlling member 25 is correspondingly curved or inclined at 41. Also, the end 42 of the controlling member 25 is curved to 85 correspond with the curvature of the bottom of the groove in the hub 21. The bottom of the groove in the hub 21 is provided with a recess at the point in the groove with which the end of the controlling member coacts when the operating shaft is at rest. This recess is shown at 43 in Fig. 10. The forward end of the recess is tapered, as indicated at 44, by the provision of an inclined wall at the forward end of the recess corresponding to the inclined wall 41 on the controlling member 25. Referring to Figs. 7, 8 and 9, particular attention is directed to the depth of the circumferential groove in the hub 21 at different points 90 100 about the circumference. The depression or recess in the bottom of the groove is shown at 43. Beyond this depression in a direction opposite to the direction of rotation of the shaft with its hub, the groove is quite shallow, as indicated at 45. This portion of the groove which is relatively shallow extends approximately half-way around the axis of the shaft. The groove then becomes deeper so that its normal depth is reached at 110 about the point indicated by the reference 46.

The operation of the mechanism constructed in this manner will now be described. The operator depresses the pedal 30, thereby 115 drawing the rods 32 and 38 down and rocking the shaft 33 carrying the guard 37 so as to move the guard from the full line position shown in Fig. 1 to the dotted line position, in which position it effectually 120 precludes injury to the operator by inserting his hand between the two dies. Also, the downward movement of the pedal and the rods 32 and 38 causes the lever 29 to be rocked on its pivot, thereby drawing the 125 controlling member 25 outwardly away from the axis of the operating shaft 17 against the tension of spring 28. This withdraws the end of the controlling member from the depression 43 in the hub of the shaft 17 130

and from the recess in the dog 22. The dog is then moved in the direction of its length by its spring 23 and its end is projected into one of the recesses in the hub of the power wheel 19. This connects the power wheel to the shaft 17 and the latter is rotated and acts through the eccentric 47 to reciprocate the slide 10 and the upper die carried thereby. The retractile movement of the controlling member 25 carries it beyond the bottom of the shallow portion 45 of the groove in the hub 21. The shaft 17 begins to rotate with the power wheel 19 and if the pedal 30 be immediately released, the springs 31 and 28 exert a tension tending to raise pedal 30 and rods 32 and 38 and move the controlling member 25 toward the axis of the shaft 17. This movement carries the end of the controlling member into contact with the bottom of the groove in the hub at the portion 45 of the groove where it is quite shallow. The outward movement of the controlling member carries it but little beyond the level of the bottom of the shallow portion of the groove so that this inward movement would be very small, so small that the accompanying upward movement of the pedal 30 and guard 37 would be so slight as to be negligible. The operating shaft continues its rotation with the end of the controlling member riding upon the bottom of the groove in the hub 21 and when the deeper portion 46 of the groove comes under the controlling member, the latter moves inwardly toward the axis of the shaft and the pedal 30 and guard 37 are raised correspondingly. When the depression 43 comes under the controlling member 25, the beveled end of the controlling member enters the recess in the dog 22 and engages the inclined wall of the recess and the cam action of these two coacting parts operates to move the dog 22 against the tension of its spring 23 so as to withdraw its end from the recess in the hub of the power wheel. This disconnects the operating shaft 17 from the power wheel. Also, the end of the controlling member enters the depression 43 and moves along therein until the inclined wall 41 of the end of the controlling member comes into engagement with the inclined wall of the tapered end 44 of the recess 43 in the bottom of the groove in the hub, and the engagement of these two walls brings the operating shaft 17 to rest. This precludes the possibility of continued rotation of the operating shaft when such continued rotation is not intended, such as is commonly termed "repeating." Of course, continued operation of the shaft 17 without interruption may be secured if desired by merely holding the pedal 30 in the depressed position, in which case the controlling member 25 would be held in its outermost position in which it is shown in Fig. 8, thus allowing the power shaft 19 to drive the operating shaft 17 as long as continuous operation of the machine is desired. But on release of the pedal 30, the controlling member 25 moves into engagement with the bottom 70 of the groove in the hub 21 and insures a discontinuance of the rotation of the operating shaft by its engagement with the wall at the end of the groove 43. In every case, however, it will be noted that the controlling member 25 is held positively in an outer position by the bottom of the shallow portion 45 of the groove in the hub 21 until the operating shaft has made substantially a half revolution and its retention in this 75 outer position insures that the guard 37 will be held in its depressed or operative position until the upper die has been lowered into engagement with the lower die. It will be noted also that the connection of the rods 80 32 and 38 to the crank 34 by releasable devices permits of shifting the angular position of the rocking frame 12 on the pedestal 11 and then readily establishing the desired connection from the pedal 30 to the guard 90 and the controlling member so that those parts will be operated by the pedal in the manner above described.

I claim:

1. A punch press having an operating shaft, a power member, a dog movable on the operating shaft in the direction of the axis of the shaft into engagement with the power member to connect the power member to the shaft, a controlling member for positioning the dog, means for moving the controlling member outwardly from the shaft to release the dog, a guard connected to the controlling member so as to be moved to its operative position when the controlling member is moved to its outer position for releasing the dog, and means for holding the controlling member in substantially the position to which it is moved to release the dog during substantially a half revolution of the operating shaft; substantially as described. 95
2. A punch press having an operating shaft, a power member, a dog mounted for movement in the direction of its length upon the operating shaft to carry its end into engagement with the power member, a controlling member whose end is adapted to enter a circumferential groove on the operating shaft to coact with the dog, a guard, and an operating device connected to the guard and to the controlling member for moving the guard to its operative position and for moving the controlling member to cause it to release the dog, the said groove being of relatively shallow depth over substantially half of its length to hold the controlling member in substantially the position to which it is moved to release the dog during substantially one-half of a revolution 130

of the operating shaft to maintain the guard in its operative position while the die reciprocated by the operating shaft is moved into engagement with the work; substantially as described.

3. A punch press having a power member, an operating shaft, a dog movable in the direction of its length upon the operating shaft to carry its end into engagement with the power member, a controlling member, a groove on the operating shaft in which the controlling member is adapted to move to coact with the dog, a guard, and an operating device connected to the guard and the controlling member, the groove in the operating shaft having a depression therein with which the controlling member coacts to arrest rotation of the shaft and having the portions thereof on opposite sides of the depression of different depths whereby when the switch is in the portion of the groove of less depth, the guard is held in its operative position; substantially as described.

25 4. A punch press comprising a power member, a die, a guard for the die, an operating shaft for the die, a clutch dog provided with a transverse groove movable longitudinally of the operating shaft for operatively connecting the shaft and power member, the operating shaft being provided with a circumferential groove, a transversely movable controlling member adapted to coact with the groove in the dog and with the circumferential groove in the operating shaft, and means for operating the guard and the controlling member whereby the dog moves to clutching position when the guard is moved to operative position and is moved to the unclutching position by the controlling member after more than half a revolution of the shaft has been completed.

45 5. A punch press comprising a power member, an operating shaft provided with a circumferential groove varying in depth, a dog provided with a transverse groove adapted to register with said circumferential groove, said dog being longitudinally movable of the operating shaft for clutching the operating shaft to the power member, a transversely movable controlling member curved to ride in said circumferential

groove and adapted to coact with the groove in the dog to withdraw it from clutching position, a guard for a die, and operating means connected to said guard and to the said controlling member.

6. A punch press comprising a power member, an operating shaft provided with a circumferential groove varying in depth, a dog provided with a transverse groove one wall of which is beveled, movable longitudinally of the operating shaft for clutching the operating shaft to the power member, a controlling member movable transversely of the operating shaft provided with a beveled edge adapted to engage with the beveled wall of the groove in the dog and move it to the unclutched position, a guard for a die, and operating means connected to the guard and the controlling member.

7. The combination in a punch press of a power member, an operating shaft, a dog movable along the operating shaft into and out of engagement with the power member, said shaft and said dog each being provided with a groove one wall of which is beveled, a transversely movable controlling member provided with a beveled end adapted to co-operate with the grooves in the dog and the shaft for moving the dog to the unclutched position, and for stopping the rotation of the shaft after the dog has been unclutched.

8. The combination, in a punch press, of a guard, a power member, an operating shaft, a clutch dog movable longitudinally along the shaft and rotatable therewith, for clutching the power member and the operating shaft together, a controlling member movable transversely of the operating shaft into and out of engagement with the dog, a spring for moving the controlling member inwardly into engagement with the dog so that the rotation of the shaft dog causes the controlling member to move the dog longitudinally of the shaft to the unclutched position, and foot-operated means for moving the controlling member out of engagement with the dog, and means for preventing said inward movement of the controlling member until substantially half a revolution of the shaft has been completed.

In testimony whereof I affix my signature.

HERMAN OSSWALD.
